UNITED STATES PATENT OFFICE.

ROBERT S. BLAIR, OF SOUTH ORANGE, NEW JERSEY, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,108,485.

Specification of Letters Patent. Patented Aug. 25, 1914.

Application filed February 21, 1910. Serial No. 545,174.

To all whom it may concern:

Be it known that I, ROBERT S. BLAIR, a citizen of the United States, residing at South Orange, in the county of Essex and 5 State of New Jersey, have invented certain new and useful Improvements in Type-Writing Machines, of which the following is a full, clear, and exact description, such as will enable others skilled in the art to which 10 it appertains to make and use the same.

This invention relates to typewriting machines, and with regard to the more specific features thereof, to type actions therefor.

One of the objects of the present invention 15 is to provide a simple and practical type action whereby the touch will be greatly improved.

Another object of the present invention is to provide a mechanism of the above character that will permit the operator to write 20 with a less expenditure of energy than has heretofore been possible.

A further object of the invention is to provide a type action with a printing instrumentality adapted to be swung toward the 25 platen without producing a reactive strain upon its pivot point.

A further object of the invention is to provide mechanism of the above nature in 30 which substantially the actuating member follows the type bar and urges it at increasing speed throughout its entire movement.

Other objects will be in part obvious and in part hereinafter pointed out.

The invention accordingly consists in the 35 features of construction, combinations of elements and arrangement of parts which will be exemplified in the construction hereinafter set forth, and the scope of the application of which will be indicated in the following claims.

In the accompanying drawings, wherein 40 is illustrated one of many possible embodiments of my invention, Figure 1 is a diagrammatic view of a central type action when in normal position and also showing the same in an intermediate position in dotted lines. Fig. 2 is a similar view with the type action in printing position.

Similar reference characters refer to similar parts throughout both views of the drawings.

Heretofore, in constructing type actions in which a swinging type bar is used, due regard to the point at which the actuating force is applied to the printing instrumen-

tality has been somewhat neglected. It is one of the aims of the present invention to cure certain defects in typewriter construction by applying the force to the type bar at 60 that point at which the best results and easiest action are obtainable. It is a well known principle of physics that if a pendulum is struck at its center of percussion the entire force of the blow will be converted 65 into rotary motion without having any effect or strain whatsoever upon its pivotal point of suspension. This invention seeks to embody this idea in the type action of a typewriting machine, that is, to pivotally 70 mount a type bar in such a manner that the means connecting the same with the key lever, or other actuating member, substantially coincides at its point of connection with the type bar with the center of percussion 75 thereof and acts in a line at substantially right angles to a line between the center of gravity and the center of percussion.

Referring now to the drawings in detail, 80 a key lever 1 is pivotally supported intermediate its ends on a fulcrum or knife edge 2 and is connected near its other end by a link 3 with a type bar 4. This type bar is pivoted at 5 to any convenient part of the machine suitable for the purpose, according 85 to the style of machine in which the present invention is embodied. Printing instrumentalities 6 are provided at one end adapted to coact with a platen 7 in a well known manner, while the opposite end 8 is weighted to 90 bring the center of percussion, which is indicated at the point 9, nearer to the pivot point 5 of the type bar. Theoretically speaking, the center of percussion is two-thirds of the length of a uniform simple pendulum 95 away from its point of suspension, but certain mechanical disadvantages would arise if the center of percussion were not brought nearer to the pivot point.

The link 3 preferably comprises two similar strips of sheet metal or the like adapted 100 to span the key lever 1 and the type bar 4 and connected in any suitable manner, as by means of pivots at either end passing through these members. The type carrier 4 is provided with a slot 10 extending from the center of percussion 9 toward the pivot point 5 through which the pivot connecting the ends of the link 3 is adapted to pass and slide therealong as the mechanism is actuated in the manner hereinafter described. 105 Above the key lever 1, and normally in con-

tact with the link 3 is a rod 11 or the like adapted to act as a fulcrum for the link 3 and along which the same slides as the key lever is depressed. As the key lever is depressed the point 12 rotates upwardly along the dotted line 13 which tends to swing the opposite end of the link 3 inwardly along the slot 10 in the type bar 4. It is also to be noted that the length of the arms into which the link 3 is divided, considering the same as a lever, will constantly change so that as the key lever is depressed the speed of the type carrier will constantly increase as the upper end of the link 3 lengthens and will have a constantly increasing rate of movement for a uniform rate of movement of the key. A suitable spring 14 is provided for returning these members to normal position and may be connected for instance to the key lever 1 and any suitable part of the frame.

The operation of this device is as follows: As the key lever 1 is depressed the opposite end is raised and the pressure transmitted through link 3 directly to the type bar 4 at substantially its center of percussion and at right angles thereto. All of the force will tend to cause a rotary movement of the latter in overcoming its inertia so that the touch will obviously be very light and easy. However, as the key lever is depressed the link 3 engaging the rod 11 will act as a lever to aid in moving the type bar and constantly urge the same toward the platen, but its point of connection therewith will gradually approach its pivotal point so that it will move at increasing speed and the impact between the type and the platen will be quick and of relatively great pressure. The parts are, of course, returned to normal position under the action of the spring 14.

It is thus seen that this invention provides for a simple and practical type action with a small number of parts, which will of course greatly reduce the cost of manufacture, and in which the entire force exerted by the operator on the key lever will be transmitted to bring the type to the printing point in the easiest manner and in the shortest possible time.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In a typewriting machine, in combination, a key lever, a type bar, and an intermediate connection between the key lever and the type bar for transmitting motion from one to the other, said connection engaging the latter substantially at the center of percussion. 75

2. In a typewriting machine, in combination, a key lever, an upwardly swinging pivoted type bar and means connecting the key lever with the type bar adapted to convey motion from one to the other and engaging the latter at substantially the center of percussion. 80

3. In a typewriting machine, in combination, a key lever, a pivoted type bar, and a link connecting the key lever with the type bar for transmitting motion from one to the other, said link engaging the latter at the beginning of its movement at substantially the center of percussion. 85

4. In a typewriting machine, in combination, a platen, a key lever, a type bar, and means for transmitting motion from the key lever to the type bar, said means engaging the latter at substantially its center of percussion at the beginning of the movement and capable of shifting its position as the type bar approaches the platen. 90

5. In a typewriting machine, in combination, a platen, a key lever, a pivoted type bar, means associated with said type bar to bring its center of percussion relatively close to its pivot point, and means connecting the type bar at its center of percussion with said key lever, whereby motion is transmitted from one to the other. 95

6. In a typewriting machine, in combination, a platen, a key lever, a pivoted type bar, a weight at one end of said type bar for bringing the center of percussion thereof in close proximity to its pivot, and a connection between the type bar at its center of percussion and said key lever. 100

7. In a typewriting machine, in combination, a platen, a key lever, a pivoted type bar, a weight at one end of said type bar for bringing the center of percussion thereof in close proximity to its pivot, a connection between the type bar at its center of percussion and said key lever, when said type bar is in normal position; and means whereby the point of contact of said type bar and said connection may change as the type bar approaches the platen. 115

8. In a typewriting machine, in combination, a platen, a pivoted key lever, a pivoted type bar, said type bar having a slot surrounding its center of percussion and a link engaging the slot at one end and the key lever at its opposite end whereby motion is transmitted from one to the other. 125

9. In a typewriting machine, in combination, a platen, a pivoted key lever, a pivoted type bar, said type bar having a slot surrounding its center of percussion, and a connection engaging the slot at one end and the key lever at its opposite end whereby motion is transmitted from one to the other, the force transmitted through said connection adapted to be applied initially at the center of percussion and to move away therefrom as the type bar approaches the platen. 50
10. In a typewriting machine, in combination, a platen, a pivoted key lever, a type bar, said type bar being pivoted adjacent its center of percussion, and a connection between the key lever and the type bar for transmitting motion from one to the other adapted to apply the initial force substantially at the center of percussion. 55
11. In a typewriting machine, in combination, a platen, a pivoted key lever, a type bar, said type bar being pivoted adjacent its center of percussion, and a connection between the key lever and the type bar transmitting motion from one to the other adapted to apply the initial force substantially at the center of percussion, the point of engagement being adapted to shift as the type bar approaches the platen. 60
12. In a typewriting machine, in combination, a platen, a pivoted key lever, a type bar, said type bar being pivoted adjacent its center of percussion, a link between the key lever and the type bar for transmitting motion from one to the other and adapted to apply the initial movement at substantially the center of percussion, the point of engagement between said link and type bar being adapted to shift as the latter approaches the platen, and means for returning said parts to normal position. 65
13. In a typewriting machine, in combination, a platen, a key lever pivoted intermediate its ends, a type bar pivoted intermediate its ends, a connection at substantially one end of said key lever adapted to engage said type bar at substantially its center of percussion, whereby pressure will be applied at that point when the key lever is depressed. 70
14. In a typewriting machine, in combination, a platen, a key lever pivoted intermediate its ends, a type bar, a link connecting said key lever with said type bar substantially at its center of percussion, and means adapted to shift the point of engagement between said link and said type bar as the latter approaches the platen. 75
15. In a typewriting machine, in combination, a platen, a key lever pivoted intermediate its ends, a type bar, a link connecting said key lever with said type bar substantially at its center of percussion, and means for increasing the speed of said type bar as said key lever is actuated. 80
16. In a typewriting machine, in combination, a platen, a key lever and a pivoted type bar, a link between the key lever and the type bar engaging the latter at substantially the center of percussion, and means for shifting said point of engagement as the type bar approaches the platen. 85
17. In a typewriting machine, in combination, a platen, a key lever and a pivoted type bar, a link between the key lever and the type bar engaging the latter at substantially the center of percussion, and means for increasing the speed of said type bar as the key lever is depressed. 90
18. In a typewriting machine, in combination, a platen, a key lever and a pivoted type bar, a link between the key lever and the type bar normally engaging the latter at substantially its center of percussion, and adapted to shift the point of engagement as the type bar approaches the platen, and means for increasing the speed of said type bar as the key lever is depressed. 95
19. In a typewriting machine, in combination, a platen, a key lever pivoted intermediate its ends, a type bar, and a link connected with said key lever at substantially its center of percussion, said type bar having a slot with which said connecting link engages and in which it is adapted to move as the type bar approaches the platen. 100
20. In a typewriting machine, in combination, a platen, a pivoted key lever, a pivoted type bar, a link connecting the key lever with the type bar at substantially its center of percussion, and means engaging the said link, whereby the speed of said type bar is increased as the type approaches the platen. 105
21. In a typewriting machine, in combination, a platen, a pivoted key lever, a pivoted type bar, a link connecting the key lever with the type bar at substantially its center of percussion, and a relatively movable member engaging said link adapted to act as a fulcrum, so that the speed of said type bar is increased as the key lever is depressed. 110
22. In a typewriting machine, in combination, a platen, a key lever pivoted intermediate its ends, a type bar having its pivot relatively close to its center of percussion, a link connected with said type bar at its center of percussion and to one end of said key lever, whereby as said key lever is depressed the force will be transmitted from said link to the type bar at its center of percussion to cause a rotary movement thereof toward the platen. 115
23. In a typewriting machine, in combination, a platen, a key lever pivoted intermediate its ends, a type bar having its pivot relatively close to its center of percussion, a link connected with said type bar at its center of percussion and to one end of said key lever. 120

key lever, whereby as said key lever is depressed the force will be transmitted from said link to the type bar at its center of percussion to cause a rotary movement there-
5 of toward the platen, and means connected with one of said parts for returning same to normal position.

24. In a typewriting machine, in combination, a key lever, a type bar, a pivot about
10 which said type bar is adapted to turn, and a connection between the key lever and the type bar for actuating the same, said type bar having a slot extending from its center of percussion toward its pivot point for receiving one end of the connection between
15 the key lever and the type bar.

25. In a typewriting machine, in combination, a type bar having a pivot point and a slot therein extending from its center of
20 percussion toward said pivot point.

26. In a typewriting machine, in combination, a type bar, and a pivot point therefor intermediate its ends, said type bar having a slot extending from its center of per-
25 cussion toward said pivot point.

27. In a typewriting machine, in combination, a type bar having a weight at one end, a pivot point intermediate its ends, said type bar having a slot extending from its
30 center of percussion toward said pivot point, said slot being on opposite side of said pivot point from said weighted end.

28. In a typewriting machine, in combination, a type bar having a weight at one end, a pivot point intermediate its ends, said type bar having a slot extending from its center of
35 percussion toward said pivot point, a key lever and a connection between the key lever and the type bar at right angles to said slot having its end normally coinciding with the center of percussion, whereby the force will be transmitted to that point when the key lever is depressed.

29. In a type action for typewriting ma-
45 chines, in combination, a type carrier, and actuating means therefor engaging the center of percussion of said type carrier.

30. In a type action for typewriting ma-
50 chines, in combination, a pivoted type car-
rier, and actuating means therefor adapted to engage said type carrier at substantially its center of percussion and act initially in a direction at right angles to a line between its pivot point and its center of gravity.

31. In a type action for typewriting ma-
55 chines, in combination, a pivoted carrier, actuating means initially engaging said type carrier at its center of percussion, and means whereby said point of engagement is shifted as the type carrier is actuated.

32. In a type action for typewriting ma-
60 chines, in combination, a pivoted type car-

rier having a slot including its center of percussion and extending toward the pivot point, and actuating means initially engag-
65 ing said slot at the center of percussion and adapted to move along said slot as the type carrier is actuated.

33. In a type action for typewriting ma-
60 chines, in combination, a type carrier, and actuating means for said type carrier oper-
70 atively connected therewith through its center of percussion.

34. In a type action for typewriting ma-
65 chines, in combination, a pivoted type car-
rier, and actuating means for said type car-
75 rier operatively connected therewith at the beginning of its movement through its center of percussion.

35. In a type action for typewriting ma-
80 chines, in combination, a type carrier hav-
ing a weighted end, a pivot point interme-
diate the weighted end and, relatively close to, the center of percussion, and means for
85 actuating said type carrier through its center of percussion.

36. In a type action for typewriting ma-
80 chines, in combination, a pivoted type carrier,
a key lever, and intermediate mechanism con-
necting said parts, including a variable le-
90 verage mechanism adapted to follow said carrier and urge it toward its printing position and throughout its entire travel up to printing position at a constantly increasing
95 rate of speed.

37. In a type action for typewriting ma-
90 chines, in combination, a type carrier, and actuating means therefor, including a link
adapted to act as a lever engaging said type carrier and adapted to follow the same to its
100 printing position and constantly increase the rate of movement thereof to the printing point.

38. In a type action for typewriting ma-
105 chines, in combination, a type carrier, an ac-
tuating member, and an intermediate vari-
able leverage mechanism connected at one
end to said type carrier at substantially its
center of percussion.

39. In a type action for typewriting ma-
110 chines, in combination, a type carrier, an ac-
tuating mechanism, a link connecting said parts, and a fulcrum engaging said link whereby the same acts as a lever, the con-
struction and arrangement of said parts be-
ing such as to constantly change the relation between said link and fulcrum as the type carrier approaches the platen.

In testimony whereof I affix my signature
in the presence of two witnesses.
